Inventor:

Lars Tensen Rud
By *Lars Tensen Rud*

UNITED STATES PATENT OFFICE.

LARS JENSEN RUD, OF HERNING, DENMARK,

DENTAL PLATE.

Application filed June 28, 1923. Serial No. 648,320.

To all whom it may concern:

Be it known that I, LARS JENSEN RUD, subject of the King of Denmark, residing at Herning, Denmark, have invented certain new and useful Improvements in Dental Plates, of which the following is a specification.

The present invention relates to dental plates; and it proposes, briefly, certain hereinafter-described improvements in the construction of devices of the character indicated whereby they are effectively held in place in the mouth during the ordinary movements of the jaws incidental to eating, speaking and laughing, without any danger of producing irritation.

In dental plates as heretofore constructed, it has usually been difficult, and in many instances impossible, particularly in the case 20 of the upper plate, to keep them in position. This is due primarily to the fact that the suction action generally relied on to hold the plate or plates in place is more or less impaired by the small open space which is 25 always present at the front of the plate between the gum portion of the same and the natural gum and which permits the entrance of air between said parts. On the other hand, however, such space has, hitherto at 30 least, been necessary, since the above-mentioned movements of the jaws require it; its absence causing irritation of the mucous membrane with resultant swelling and pain, by reason of the friction which would then 35 be exerted upon the muscles of the natural gum.

According to my invention, these drawbacks are avoided by providing the body of the plate, which is made of hardened rubber, with an attaching strip of soft rubber so constructed that it will always follow the movements of the natural gum and, in consequence, prevent the formation of the aforesaid open space and the entrance of air therethrough.

In the accompanying drawing:

Figure 1 is a transverse sectional view of an upper plate embodying the invention, and Fig. 2 is a similar view of a lower plate.

Referring more particularly to said drawing, the teeth 1 are fastened in the usual way to an artificial gum 2 which is made of hard rubber. In the case of the upper plate, 55 this part 2 is shaped to fit the roof of the mouth, as well as the natural gum, whereas

the plate for the lower jaw fits the natural gum only, as will be understood.

In both cases, however, there is secured to the hard rubber part or member 2 a strip 60 of soft or elastic rubber 3; and this strip is fixed, in the case of the upper plate (Fig. 1), to the upper face thereof at the marginal edge, and, in the case of the lower plate, to its lower face, so as to coact directly 65 with the front or outer surface of the natural gum; the strip on the lower plate being so shaped as to also engage the inner surface of said gum.

The essential feature of the strip 3 is the 70 fact that it is of gradually increasing thinness from its base or root to its edge or tip; due to which construction, its aforesaid edge is rendered much more flexible than its base and will not only adhere closely and tightly 75 to the natural gum, but also will follow all the movements of the muscles of the gums. This adhesion will effectively prevent the entrance of air between the plate and the natural gum; and since such adhesion will be 80 maintained throughout the movements of the jaws, the plate will be securely held in position instead of becoming loosened thereby.

The upper plate is preferably completed 85 by an additional strip 4 of soft or elastic rubber, which is located on and secured to the inner or upper face thereof adjacent the rear edge, and which projects at opposite ends against the inner face of the strip 3. 90 This strip 4 will engage the roof of the mouth and thus prevent the entrance of air at the rear of the plate.

I claim as my invention:

1. A dental plate comprising a hard rubber member, to one side of which the artificial teeth are fastened, and a strip of soft rubber secured to the other side of said member and having a cross-sectional area of gradually increasing thinness from its base to its outer edge; whereby said edge is rendered extremely flexible and is enabled to adhere closely and tightly to the adjacent surface of the natural gum when the plate is in place so as to prevent the entry of air between the gum and plate, substantially as described.

2. A dental plate, comprising a hard rubber member, to one side of which the artificial teeth are fastened, and a strip of soft rubber secured to the other side of said member and having a thin, flexible free edge which is adapted to adhere closely and tight-

ly to the adjacent surface of the natural gum when the plate is in place; substantially as described.

3. A dental plate, comprising a hard rubber member, to one side of which the artificial teeth are fastened, embodying a central portion adapted to fit against the roof of the mouth; a narrow strip of soft rubber secured to the other side of said member at the edge thereof and having a thin, flexible free edge which is adapted to adhere closely and tightly to the adjacent surface of the natural gum when the plate is in place; and a narrow strip of soft rubber located on and secured to the upper face of the said central portion of said member adjacent the rear edge thereof so as to directly engage the roof of the mouth.

4. A dental plate, comprising a hard rub-

ber member, to one side of which the artificial teeth are fastened, embodying a central portion adapted to fit against the roof of the mouth; a narrow strip of soft rubber secured to the other side of said member at the edge thereof and having a gradually-increasing thinness from its base to its upper edge, whereby said edge is rendered extremely flexible and is enabled to adhere closely and tightly to the adjacent surface of the natural gum when the plate is in place; and a narrow strip of soft rubber located on and secured to the upper face of the said central portion of said member adjacent the rear edge thereof so as to directly engage the roof of the mouth.

In testimony whereof I affix my signature.

LARS JENSEN RUD.
